CLAIM

The ornamental design for a bottle closure, as shown and described.

DESCRIPTION

A portion of the disclosure of this patent document contains material which is subject to copyright protection. This patent document may show and/or describe matter which is or may become trade dress of the owner. The copyright and trade dress owner has no objection to the facsimile reproduction by anyone of the patent disclosure as it appears in the Patent and Trademark Office patent files or records, but otherwise reserves all copyright and trade dress rights whatsoever.

FIG. 1 is a top view of the bottle closure showing our new design;

FIG. 2 is a bottom view of the bottle closure;

FIG. 3 is a right side view of the bottle closure;

FIG. 4 is a left side view of the bottle closure;

FIG. 5 is a rear view of the bottle closure;

FIG. 6 is a front view of the bottle closure;

FIG. 7 is a front perspective view of the bottle closure; and,

FIG. 8 is a rear perspective view of the bottle closure.
